UNITED STATES PATENT OFFICE.

GEORGE JOHN, OF DETROIT, MICHIGAN, ASSIGNOR OF ONE-HALF TO ELEES AMOUNEY,
OF DETROIT, MICHIGAN.

TOP-SPINNING DEVICE.

1,208,975.

Specification of Letters Patent. Patented Dec. 19, 1916.

Application filed September 15, 1916. Serial No. 120,242.

To all whom it may concern:

Be it known that I, GEORGE JOHN, a subject of the Sultan of Turkey, residing at Detroit, in the county of Wayne and State of Michigan, have invented certain new and useful Improvements in Top-Spinning Devices, of which the following is a specification, reference being had therein to the accompanying drawings.

10 This invention relates to a top spinning device by which an ordinary wood conical-shaped top may be spun, instead of using the customary string and throwing the top to impart a spinning movement to the same.

15 My invention aims to provide a simple, durable and easily operated top spinning device wherein a coiled spring is employed for imparting a rotary movement to a top. The spring is placed under tension by placing 20 the top in engagement with a convolution thereof and then rotating the top to wind the spring. The spinning device has a spring-pressed latch adapted to temporarily hold the top and adapted to be manually 25 actuated to release the top.

The detail construction of the top spinning device will be hereinafter specifically described and then claimed, and reference will now be had to the drawings, wherein—

30 Figure 1 is a vertical sectional view of the spinning device and top, showing the latter in position to be spun; Fig. 2 is a bottom plan of the top spinning device; Fig. 3 is a top plan of the top, and Fig. 4 is a side elevation on a small scale of a top spinning device and top.

In the drawing 1 denotes a knob or handle having a longitudinal central bore 2 with the end of the bore open at the lower end of the 40 handle. Mounted in the handle 1 and extending through the bore 2 and protruding from the lower end of the handle is a cylindrical stem 3, and this stem, within the bore 2 is encircled by a coiled spring 4 having the 45 inner convolution thereof connected to the stem 3, as at 5, and the outer convolution terminating in a hook 6.

The handle 1, at one side of the bore 2, has a longitudinal auxiliary bore 7 and a slot 50 8 communicating with the auxiliary bore. Slidable in the auxiliary bore is a latch 9 normally held in an extended position by a coiled compression spring 10 in the inner end of the auxiliary bore 7. The latch 9 is 55 adapted to be manually retracted by a but-

ton 11 having a shank extending through the slot 8 into the inner end of the latch 9.

12 denotes an ordinary wood and conical shaped top having a plug 13. The top 12 is provided with a central longitudinal stem socket 14 adapted to receive the lower end of the stem 3 and the upper end of the top has latch sockets 15 disposed circumferentially of the stem socket 4. The upper end of the top 12 also has a pin 16 adapted to 65 engage the hook 6 of the spring 4 and wind said spring as the top 12 is rotated upon the stem 3. Normally a few of the convolutions of the spring 4 protrude from the lower end of the handle 1, and when the 70 hook 6 is engaged by the pin 16 and the spring placed under tension, the lower convolutions recede into the open end of the bore 2 and permits of the upper end of the top 12 assuming a position in close proximity 75 to the lower end of the handle 1.

When the spring 4 is placed under tension by rotating the top 12, the spring-pressed latch 9 engages in one of the latch sockets 15 and temporarily holds the top 12 upon the 80 stem 3. When the latch 9 is manually retracted, the spring 4 simultaneously ejects the top 12 from the stem 2 and in so doing imparts a spinning movement to the top so that the top will spin on a floor or other 85 surface.

With the spring 4 under tension and set to rotate the top 12, the walls of one of the latch sockets 15 will frictionally engage the latch 9 and thereby preclude any possibility 90 of the spring 4 ejecting the top so long as the latch is in one of the latch sockets.

I attach considerable importance to the simplicity of construction which permits of the toy being manufactured at comparatively low cost, and it is practically impossible for a child to be injured when manipulating the device.

What I claim is:

A top spinning device comprising a handle having a central longitudinal bore, a stem of less diameter than the bore of said handle and having the inner end thereof mounted in said handle, and the outer end thereof protruding from the lower end of 105 said handle, a coiled spring encircling said stem within the bore of said handle and having the inner convolution thereof connected to said stem and the outer convolution terminating in a hook, a top having a stem 110

socket adapted to receive the lower end of said stem, said top having the upper end thereof provided with sockets circumferentially of the stem socket, a pin carried by the upper end of said top adapted to engage the hook of said spring and place said spring under tension when said top is rotated upon said stem, a spring pressed latch in said handle adapted to engage in one of the latch 10 sockets of said top, and a button operable at

the side of said handle adapted for retracting said latch to release said top so that said spring may eject said top from said stem and impart a spinning movement thereto.

In testimony whereof I affix my signature 15 in the presence of two witnesses.

GEORGE JOHN.

Witnesses:

ANNA M. DORR,
KARL H. BUTLER.
